CAN END COATING MACHINE

Scott R. Johnson and Ralph M. Mero, Chicago,
Ill., assignors to Continental Can Company,
Inc., New York, N. Y., a corporation of New
York

Application December 28, 1948, Serial No. 67,668

2 Claims. (Cl. 113—80)

1

This invention has to do with new and useful improvements in a can end coating machine. In the patent granted Nelson Troyer and Merton L. Dodge, August 16, 1927, No. 1,639,118 there is shown a can end coating machine which includes a rotating turret having mounted thereon a series of coating or lining units. Each unit includes a pair of chucks between which a can end is mounted. Means is provided for rotating the chucks. Associated with the chucks is a nozzle which is disposed over the channel in the can end for directing a coating material into the channel. Associated with the nozzle is a needle valve. The needle valve is operated by a control cam and devices which are so timed as to open the valve for a coating operation after which the valve is closed.

The machine also includes means whereby the valve actuating devices are rendered inoperative so that the valve remains closed provided there is no can end to be coated. The means which renders the valve operating mechanism inoperative includes latches which are so disposed that when it is desired to stop the machine the latch may be released so that the valve actuated thereby is closed.

An object of the present invention is to provide a means for automatically closing the valves controlling the coating of the ends in case the machine is stopped so that a can end being coated will not receive an excess of coating material.

A further object of the invention is to provide centrifugally operated control devices for releasing the coating valves so that the springs associated therewith will close the same when the machine stops, which control means is ineffective when the machine is operating at high or low speeds.

Figure 1 is a view, more or less diagrammatic and in vertical section, showing a portion of one of the coating units and the valve actuating mechanism therefor and also the means for automatically closing the valves when the machine stops, the control means for the valve being shown in the position it assumes when the machine is in operation.

Figure 2 is a view similar to Figure 1 but shows the control means in the position it assumes when the machine is stopped.

Figure 3 is a vertical sectional view showing the nozzle and the valve controlling the same, and its relation to the can end being lined.

The machine to which the present improvement has been applied is the same as that shown and described in the Troyer et al. patent supra, 55

and only the parts essential to the carrying out of the present invention are shown and will be described in detail.

The can end is indicated at C. The can end is clamped between a lower chuck 10 and an upper chuck 11. These chucks are rotated by suitable mechanism. Associated with the chucks is a coating nozzle 12. This coating nozzle 12 is provided with a passage 13 leading to a passage 14. The passage 14 is connected to a supply tank provided with coating material. The nozzle includes a nipple 15 which is secured to the nozzle by means of a threaded collar 16. This nipple has a small opening disposed directly above the channel 17 in the can end and through this opening the coating material flows onto the can end.

Associated with the nipple 15 is a needle valve 18. The needle valve 18 is rigidly connected to a rod 19. A diaphragm 20 is secured to this rod 19 and this diaphragm is clamped to the supporting bracket for the nozzle so as to provide a fluid tight connection between the rod 19 and the chamber in the nozzle bracket.

There is an actuating cam 21 which is provided with a cam groove 22 in which a roller 23 runs. The roller 23 is carried by a lever 24 pivoted at 25 to a post 26 which extends upwardly through a bearing sleeve 27 carried by a bracket 28 which is secured by bolts 29 to the frame of the machine. The rod 19 carrying the needle valve extends upwardly through the upper frame member 30 of the turret of the machine and a spring 31 bearing against the frame member and against a collar 32 fixed to the rod 19 tends to move the rod downwardly and to close the needle valve. The lever 24 extends beyond the pivot and has a rounded head 33 engaging between spaced collars 32 and 34 on the rod 19. When the roller 23 is moved downwardly by the cam groove 22 then the lever will be oscillated so as to lift the needle valve and permit the coating material to flow into the channel on the can end. This cam groove 22 is so shaped that the needle valve is opened only a sufficient time for a coating operation after which it is closed so that the coated can end can be removed from the chucks and another end placed between the chucks for the next coating operation.

The post 26 is locked in raised position by means of a latch arm 35 pivoted at 36 to the bracket 28. This latch arm carries a hardened metal plate 37 which is adapted to engage beneath a shoulder 38 on the plate 39 attached to the post. When the latch is in the position

shown in Figure 1, downward movement of the post is prevented and the roller moving downwardly in the can groove 22 will lift the rod 19 and open the nozzle for a coating operation.

Centrally of the upper chuck 11 is a rod 40. This rod carries a pad 41 which rests on a can end C when there is a can end placed between the chucks. When the rod is held in its raised position, the upper end 42 of the rod 40 engages beneath an abutment arm 43 mounted for free movement on the pivot pin 36. There is a spring 44 between this abutment plate and the latch. The abutment plate rests on the upper end of the rod 40 which will be held raised by the can end. This will compress the spring 44 so as to hold the latch in engagement with the shoulder 38 on the post 26. If there is no end to be coated then the rod 40 and the pad 41 will be moved downwardly by the spring 45. This releases the support for the abutment plate 43, and the decreased compression of the spring 44 will permit centrifugal force resulting from rotation of the member 30 when the machine is operating to move the latch arm 35 to the open position shown in Figure 2. When the latch is moved to the open position the post 26 is released and permitted to move downwardly.

The downward movement of roller 22 caused by the continuous movement of the cam 21 will then be ineffective to lift the needle valve and said valve will be held closed by the pressure of the spring 31 when released.

Applicant's improvement resides in devices which are automatically brought into action when the machine stops for releasing the latches so that if the needle valve is open it will be moved to closed position by the spring 31. The bracket 28 extends upwardly so as to overhang the latch 35 as indicated at 28^a. Mounted on the inner face of this extension of the bracket 28 is a lever 46 which is pivoted to the extension at 47. The lower end of this lever 46 is provided with a rounded portion 48 which lies close to the latch when the latch and lever are positioned as shown in Figure 1. However, at this time the lever 46 does not in any way prevent the releasing of the latch if there is no end to be coated.

Mounted on the extension 28^a is an arm 49 which is pivoted to the extension at 50. Said arm 49 is provided with a bracket portion 51 to which a cylindrical weight 52 is bolted. This bracket portion 51 carries an arm 53, the free end 54 of which lies close to the end 55 of the lever 46. When the machine is in operation this weighted member 52 will be swung outwardly from the vertical line of suspension by centrifugal force and will be positioned as shown in Figure 1. When however the machine stops then the weighted member will swing back to a vertical suspended position as shown in Figure 2.

When the machine is in operation the weight assumes the position shown in Figure 1 and the lever 46 is out of contact with the end 54 of the bracket 51. It is also out of contact with the latch so that the control means for releasing the latch when there is no end to be coated is free to operate. If the machine is stopped then the weight 52 will swing to the position shown in Figure 2 and the end 54 of the arm 53 will engage the end

55 of lever 46 and move the lever to the position shown in Figure 2. This swinging movement of the lever 46 causes the end 48 thereof to engage the latch 35 and move the same so as to release the post 26. When the post is released so that it can move downwardly, the spring 31 will force the rod 19 downwardly for closing the valve.

There is a weight associated with each coating unit and these weights operate automatically when the machine is stopped to render the valve actuating mechanism inoperative and also release the valves so that the springs associated therewith will move the valves to closed position.

15 It is obvious that minor changes in the details of construction may be made without departing from the spirit of the invention as set forth in the appended claims.

I claim:

20 1. A machine for coating can ends comprising a rotatable turret, a plurality of coating units carried by said turret, each unit including a rotatable chuck for supporting the can end to be coated, a coating nozzle associated with said chuck, a valve controlling said nozzle, an actuating cam and devices operated thereby for opening and closing said valve for a coating operation, said cam actuating devices including a fulcrum post, a latch for holding the fulcrum post in raised position for permitting the actuating cam to open the valve, devices associated with the chuck for releasing the latch when there is no can end to be coated, and gravity actuated devices operating independently of said first 25 named devices for automatically releasing the latch for causing the valve associated therewith to close when the machine stops with a can end on the chuck.

2. A machine for coating can ends comprising a rotatable turret, a plurality of coating units carried by said turret, each unit including a rotatable chuck for supporting the can end to be coated, a coating nozzle associated with said chuck, a valve controlling said nozzle, an actuating cam and devices operated thereby for opening and closing said valve for a coating operation, said cam actuating devices including a fulcrum post, a latch for holding the fulcrum post in raised position for permitting the actuating cam to open the valve, devices associated with the chuck for releasing the latch when there is no end to be coated, a weighted member movable by centrifugal force away from the latch when the machine is in operation and toward the latch by gravity when the machine is stopped, and devices operated by the weighted member for releasing the latch when the machine is stopped to cause the valve to close when a can end is on the chuck.
